US0D1075579S

(12) **United States Design Patent** (10) **Patent No.:** **US D1,075,579 S**
(45) **Date of Patent:** **** May 20, 2025**

(54) **ELECTRIC BICYCLE**

(71) Applicant: **Invanti (Beijing) Technology Co., Ltd.**, Beijing (CN)

(72) Inventors: **Chunyuan Xu**, Beijing (CN); **Chongyang Shi**, Beijing (CN); **Jianguo Jiang**, Beijing (CN); **Lijian Li**, Beijing (CN)

(73) Assignee: **Invanti (Beijing) Technology Co., Ltd.**, Beijing (CN)

(**) Term: **15 Years**

(21) Appl. No.: **29/894,803**

(22) Filed: **Jun. 14, 2023**

(30) **Foreign Application Priority Data**

May 30, 2023 (CN) 202330325096.9
